UNITED STATES PATENT OFFICE

2,440,395

LEVER RELEASE LATCH

Frank S. Deschermeier, Chicago, Ill., assignor, by
mesne assignments, to Chicago Forging and
Manufacturing Company, Chicago, Ill., a cor-
poration of Delaware

Application February 7, 1946, Serial No. 646,101

1 Claim. (Cl. 292—221)

1

My invention relates to an improvement in latches and has for one purpose to provide a structure adaptable for a hood latch for automobiles and the like.

Another purpose is to provide a hood latch structure in which a minimum of effort is necessary in order to release the latch.

Another purpose is to provide improved keeper engaging means for permitting a relatively easy latch release.

Other purposes will appear from time to time in the course of the specification and claim.

The invention is illustrated more or less diagrammatically in the accompanying drawings wherein:

Figure 1 is a side elevation with parts in vertical longitudinal section;

Figure 2 is a section on an enlarged scale on the line 2—2 of Figure 1;

Figure 3 is a section on the line 3—3 of Figure 2;

Figure 4 is a section on the line 4—4 of Figure 3 with the parts in a different position;

Figure 5 is a section on the line 5—5 of Figure 4; and

Figure 6 is a detail.

Like parts are indicated by like symbols throughout the specification and drawings.

Referring to the drawings, it generally indicates an automobile hood extending forwardly from an instrument panel 2. 3 is a hood closure, herein shown as of the alligator type, which may be movably or rotatably supported in relation to the hood, as at 4. 5 illustrates the forward end of the hood closure with any appropriate louvres which do not form part of the present invention.

Mounted on the hood, by any suitable means, preferably adjustable, is the bottom plate structure generally indicated as 10. It may for example be secured by a plurality of screws or bolts 11 which pass through a supporting ledge 12. As is shown in Figure 3 the screws or bolts 11 may pass through apertures of sufficient clearance to permit a substantial adjustment in a horizontal plane of the member 10 in relation to the hood or body of the automobile. The plate 10 is provided with an aperture 13, shown as surrounded by a downwardly turned reinforcing flange 14. The plate is also provided with a dovetail aperture 15 partly surrounded by a flange 16, the flange being interrupted, as at 17, as will be clear from Figure 4 which illustrates the plate 10 from below.

Mounted preferably adjustably on the hood

2

closure is an upper plate 20 which is shown as carrying a keeper of what may be called the spear head type, the keeper including a generally vertical stem 21 screw threaded for adjustment in any suitable nut 22, which may be secured to or be held against rotation in the pocket 23 of the plate 20. At the lower end of the stem 21 is a downwardly conic keeper head 24 having at its upper end a cylindrical portion 25 terminating in a generally horizontal shoulder 26 which serves as the keeper portion proper. A coil spring 27 normally urges the cup 28 downwardly toward or against the shoulder 26 of the keeper head 24. When the parts are in the locked position, in which they are shown in Figure 3, the lower flange 29 of the cup 28 engages the upper face of the plate 10, about the edges of the aperture 15.

Mounted on the upper plate 20 is a manually controllable safety release hook generally indicated as 30. It is pivoted as at 31 to ears downwardly extending from the plate 20. Any suitable spring 32 is employed to urge it generally counter clockwise, referring to the position in which the parts are shown in Figure 3. This is effective to keep the hook proper, 33 in vertical alignment with the flange 14 at the right hand margin of the aperture 13, referring to the position of the parts of Figure 3. Thus, when the below described latch is released, the spring 27 is effective partly to raise the hood. However, if the hood is raised far enough to engage the hook 33, with the flange 14, it could go no farther unless and until the user inserts his fingers and engages the lifting lever portion 34 of the hook assembly.

Assume that the closure 3 is in the closed position in which it is shown in Figure 3. The following latch structure then becomes operative. A latch member proper is indicated at 40, and is pivoted to the lower surface of the plate 10, as at 41, for rotation about a generally vertical axis. The member 40 is also provided with an extension 42 which is guided by a strap or guide 43 having ends 44 secured by any suitable bolts or rivets or welds 45 to the lower surface of the plate 10. The plate 10 may advantageously be somewhat upwardly bulged as at 50, to give room for movement of the latch 40 and its associated parts. It may also have a further upward bulging 51 the purpose of which will later appear. In order to operate the latch 40 I provide an actuating lever 55 which is pivoted to the latch as at 56. The actuating lever and the latch are normally drawn toward latching position. I illustrate for example a coil spring 58 secured at one end to an ear 59 upset from the plate 10 and

at the other end to a pin 60 on the actuating lever 55. The end of the actuating lever 55 is adapted to abut against the cylindrical side portion 25 of the spear head 24. It is shown in this position for example in Figures 2, 3 and 4. At the same time, the latch 40 is in position overlying the upper face 26 of the spear head 24. In order to release the latch 40 I provide a flexible actuating connection, including the wire 60 which may extend to any suitable manual operating device 61. The wire may pass through any suitable conduit 62 and has a free end 63 which passes through any suitable lug or ear 64 at the end of the actuating lever 55. 65 is any suitable collar secured to the end of the wire 63.

Assume that the parts are in locking position, as shown for example in Figure 2, the user may release the latch by pulling on the wire 60. The result is to force the outer end of the actuating member 55 forcibly against the opposed face 25 of the spear head, as at the point marked X in Figure 4. The point X serves as the fulcrum of movement of the actuating lever 55. However, as the actuating lever moves clockwise, referring to the position in which the parts are shown in Figure 4, it is also effective, through its pivotal connection 56, to rotate the latch 40 about its center 41. The result is an eventual movement of the latch 40 out of its overlying locking position in which it is shown in Figure 3. As soon as the latch 40 clears the shoulder 26 of the spear head 24, the spring 27 is then effective slightly to raise the closure 3, pushing the spear head 24 upwardly through the aperture 15. After the spring 27 has partially raised the closure, the user can now grasp the outer end of the closure 3 and lift it. The lever portion 34 of the hook 30 is so formed and placed, in relation to the closure, that the user, in lifting the closure, finds it convenient to insert his fingers beneath the lever 34, whereby he may with one hand, at the same time release the hook 33, out of vertical alignment with the flange 14, and raise the closure.

Note that the latch 40 is provided with an upwardly extending stop lug 40a which limits the relative rotation of the latch 40 and the actuating lever 55. Note also that the guide 43 is so

formed and placed as to permit the movement of the latch 40 from the latching to the unlatching position or back, while maintaining it in proper horizontal alignment and in close proximity to the lower face of the plate 10.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

15 I claim:

In a latch assembly, a supporting plate having a keeper receiving aperture, a keeper adapted to penetrate the aperture and move toward and from the plate in a plane generally perpendicular to the supporting plate, a latch element on the side of the plate farthest removed from the direction from which the keeper approaches, said latch element being pivoted to the late and having a portion adapted to engage the keeper, an actuating lever pivoted to said latch element, and having an abutting portion adapted to engage a side of said keeper, yielding means adapted normally to urge said latch element and said actuating lever toward latching position, and means, engaging an outer portion of said actuating lever, for rotating it and the latch element, toward unlatching position, while maintaining a leverage contact between said actuating lever and the keeper.

35 FRANK S. DESCHERMEIER.
